(57) **CLAIM**

The ornamental design for a tire for automobile, as shown and described.

DESCRIPTION

1. Tire for automobile

1.1 is a front elevation view of a tire for automobile embodying my new design;

1.2 is an enlarged and partial front elevation view thereof for area marked as A-B in 1.1;

1.3 is an enlarged and partial front elevation view thereof for area marked as C-D in 1.1;

1.4 is a rear elevation view thereof;

1.5 is a top plan view thereof;

1.6 is a bottom plan view thereof;

1.7 is a right side elevation view thereof;

1.8 is a left side elevation view thereof;

1.9 is an enlarged and partial cross-sectional view thereof taken along line E-E in 1.2 and showing only the end face at the line E-E in 1.2;

1.10 is an enlarged and partial cross-sectional view thereof taken along line F-F in 1.2 and showing only the end face at the line F-F in 1.2;

1.11 is an enlarged view of the area marked as G-G in 1.9;

1.12 is an enlarged view of the area marked as H-H in 1.9;

1.13 is an enlarged view of the area marked as I-I in 1.10; and

1.14 is an enlarged view of the area marked as J-J in 1.10. The broken lines in the drawings illustrate portions of the tire for automobile that form no part of the claimed design.

1 Claim, 14 Drawing Sheets
